THOMAS D. CAMPBELL,

By Attorney.

UNITED STATES PATENT OFFICE.

THOMAS D. CAMPBELL, OF CLEVELAND, OHIO, ASSIGNOR TO THE CLEVELAND FOLD-
ING MACHINE COMPANY, OF CLEVELAND, OHIO, A CORPORATION OF OHIO.

METHOD OF KNUURLING.

Application filed November 3, 1923. Serial No. 672,690.

My invention relates to improvements in method of knurling and the knurled roll produced thereby; the object of my invention being the production of knurled articles 5 that shall have "lands" fabricated longitudinally thereof approximately of equal height.

In the particular art to which my invention is applied, viz, the production of knurled rolls for paper-handling mechanism, 10 it is necessary to grind the lands as originally knurled, while leaving a material cup or depression between adjacent lands. In the ordinary type of knurled roll the lands were unequally elevated so that it was impractical to grind more than one of the 15 paired lands extending longitudinally of the rolls. However, it is apparent that if the lands may be equally elevated, both lands of each pair separated by a cup or depression may be equally ground, while leaving the cup of adequate depth, if the 20 lands are sufficiently elevated.

Accordingly, I have devised a simple and novel mode of knurling rolls or similar 25 articles whereby the fabricated lands may be made substantially equal in height and sufficiently elevated above their intervening cups to admit of grinding both lands, whereby the use of the roll is very materially increased. In practicing the method of knurling these rolls hitherto, it has been thought necessary to subject the rolls to the action 30 of the knurls advanced longitudinally thereof from end to end. Invariably the lands thus fabricated are materially unequal in 35 height, with the disadvantage noted above.

I have discovered that by the simple expedient of twice knurling a roll or other cylindrical article, and in reverse or opposite directions, it is possible to produce lands 40 of substantially equal elevation upon the opposite sides of longitudinal cups or depressions extending lengthwise of the work or roll, and of sufficient depth to permit the dressing or grinding of both lands without impairing the operative qualities or efficiency of the fabricated roll. Its wearing qualities are doubled.

It will be desirable to explain the details 50 of my invention in connection with the accompanying drawings, wherein:

Figure 1 is a plan view of a lathe broken away at its ends, wherein my improved method may advantageously be practiced.

Fig. 2 is a similar side elevation thereof,

Fig. 3 is a transverse section on line 3—3, Fig. 1,

Fig. 4 is an enlarged plan view of two co-acting rolls broken away near their ends,

Fig. 5 is a transverse section on line 5—5, Fig. 4,

Fig. 6 is a greatly exaggerated fragmentary view in cross section of a roll knurled after the usual manner,

Fig. 7 is a similar view of a roll knurled in accordance with my invention,

Fig. 8 is another greatly exaggerated view of the latter roll with the lands dressed or ground to a common diameter,

Fig. 9 is an enlarged, fragmentary, dimensional section, illustrating the initial knurling operation, and

Fig. 10 is a similar fragmentary, dimensional section, illustrating the completed knurling operation, it being understood that the figures are not drawn to the scale.

Throughout the several figures of the drawings I have employed the same character of reference to indicate similar parts.

Referring first to Figs. 1, 2 and 3, the work or roll *a* is shown positioned in a lathe having the usual travelling support *b* actuated by the under screw *c* for effecting the travel of said support longitudinally of the lathe bed *d*. Two sets of opposing knurls *e*, *e'* (a plurality of knurls preferably being employed in tandem to insure the desired width of knurling members) are mounted upon said support to engage the work or roll; the usual member *a'* being provided at the extreme right of the roll to effect the alinement or register of the opposing sets of knurls previous to their engagement with the work *a*.

The travel of the support and knurls is toward the left as indicated by the arrow, and the work, under high magnification, will appear approximately as shown in Fig. 6 on a fragmentary section taken on line 6—6. Referring to the greatly enlarged section, which should be understood to be typical of ordinary knurling, it will be seen that the righthand lands *f* are materially higher than are the thicker lefthand lands *g*, so that it is impracticable to dress or grind the latter and leave a material cup or depression *h* between such lands.

Moreover, the grinding of both lands would blunt the more elevated members of the pair, if this operation were attempted, while practically destroying the cup or depression and render-

ing the roll unfit for service in paper-handling mechanism.

The reverse milling of the roll, after it has been completely milled longitudinally in one direction, may be accomplished either by reversing the direction of the actuating screw *c* in the lathe, or with better results ordinarily, by reversing the work end for end in the lathe and re-knurling the roll 10 from right to left in the lathe, as before.

This reverse knurling operation serves to produce lands of substantially equal height such as shown at *i*, *i* in the greatly enlarged fragmentary section of Fig. 7. Moreover, 15 the longitudinal depression or cup *h* is of sufficient depth, so that when the acute edges of the lands are dressed or ground as shown at *i'*, *i'*, Fig. 8, said cup *h* will insure an operative working face for the roll having 20 substantially double the wearing qualities of the rolls knurled in accordance with present methods.

In Figs. 4 and 5 the ends of two co-acting rolls *a*, *a* are shown broken away and in 25 cross section, respectively, with their hardened terminal bands *a''*, *a''* in bearing engagement and the operative faces of the rolls slightly separated. This latter feature necessarily is exaggerated for the purposes of 30 illustration, since these bands are made only from .00025" to .0005" larger in diameter than are the finished or dressed rolls, in order that the knurled operative faces may handle the thinner classes of paper, such as 35 Bible stock, in folding machines and the like.

While the re-knurling in reverse direction is very simply and readily accomplished, it has never been attempted prior to my invention 40 45 so far as I am advised, yet the results are distinctly advantageous in producing a better knurled article, i. e., one that is knurled uniformly throughout its operative face and is capable of being ground or dressed to a uniform diameter with respect to its lands, while preserving the intervening cup or depression. It is apparent that with 50 duplicated ground lands a paper-handling roll will have twice the effective life as compared with the knurled rolls of the prior art.

As a specific example of knurling high carbon rolls for paper-handling machines, such as folding machines and the like, I may instance the initial knurling of the roll from 55 right to left with an increase in its operative diameter of from .006" to .007". This operation is diagrammatically indicated in Fig. 9 of the drawings wherein the radial increase of one-half the above figures is shown 60 with respect to the land *f* upon the right. The reverse operation of knurling prefer-

ably is accomplished by closing the knurls slightly upon the work; actuating the screw *b'* (Fig. 3) for this purpose. Thereupon it will be found that the lefthand land will be 65 raised substantially to the same height as the one on the right, while the latter will be further elevated approximately .001" to .0015"; these dimensions being indicated in the diagram of Fig. 10, of which the fragmentary 70 section of Fig. 7 is typical. These dimensions, of course, are given merely by way of illustration in adapting my invention to the specific purpose indicated. The displacement and shaping of the metal quite obviously are largely under the control of the artisan and the reverse operation of knurling, preferably with closer adjustment of the knurls, alone is required for the fabrication of rolls capable of much longer 75 continued use than was hitherto possible. 80

Having now described the preferred method for practicing my invention and for producing the new and novel article of manufacture above described, I claim as new, 85 and desire to secure by Letters Patent, together with such modifications as may be made by those ordinarily skilled in the art, the following:

1. The herein described method of fabricating knurled rolls, which consists in subjecting the roll progressively to the action of the knurl throughout its length and completing the knurling action in a reverse direction, substantially as set forth. 90

2. The herein described method of fabricating knurled rolls for handling paper and the like, which consists in subjecting the roll to the action of opposing knurls advanced longitudinally in one direction and completing the knurling action by effecting the relative advance of the knurls along the roll in the opposite direction, substantially as set forth. 100

3. The herein described method of fabricating knurled rolls, which consists in subjecting the roll progressively to the action of the knurl throughout its length, completing the knurling action in a reverse direction whereby lands are produced of substantially 105 equal height, and grinding said lands to produce a working surface of uniform diameter, substantially as set forth.

4. The herein described method of fabricating knurled articles, which consists in subjecting the blank to the action of opposing knurls and re-subjecting the blank to the action of knurls more closely approximated to each other, substantially as set forth. 115

In testimony whereof I do now affix my 120 signature.

THOMAS D. CAMPBELL.
